ELECTRICAL CONNECTOR

Einar R. Olson, Richmond, Ind., assignor to
 Belden Manufacturing Company, Chicago, Ill.,
 a corporation of Illinois

Application August 17, 1939, Serial No. 290,553

2 Claims. (Cl. 173—269)

This invention relates to electrical connectors and particularly to mono-cord, plug type connectors for use with plug-in jack stationary contacts or the like.

Connectors of this type usually comprise a cylindrical, metallic, terminal contact of suitable dimensions, an insulated lead wire, the conductor of which is attached to the rear portion of the contact, and a suitable grip or sleeve, preferably of insulating material, disposed about the rear portion of the contact and possibly about the adjacent portion of the lead wire for enclosing the connection therebetween and for facilitating the grasping of the connector during its use.

In many applications of such connectors, they are constantly being subjected to bending and tension stresses, and breakage of the lead wire conductors has been a common and most troublesome occurrence. To overcome this difficulty, a sleeve or grip element has been molded in place on the conductor and contact in an effort to securely connect the conductor and contact by means independent of the normal electrical connection between the conductor wire and contact. This arrangement does not entirely solve the problem, however, for the reason that it is very difficult to satisfactorily mold such a sleeve onto the lead wire without subjecting the lead wire conductor to considerable stress. Further, such a molding operation is relatively expensive, and in view of the extremely large number of these devices which are used, the cost of manufacture is a very important consideration.

The principal object of the present invention, therefore is to provide a low cost connector of the above described type which shall include means for minimizing the stresses induced in the lead wire conductor during the manufacture and use of the connector and which at the same time shall be less expensive to manufacture than the prior art devices.

A further object of the invention is to provide a connector which may be readily assembled by relatively unskilled labor without the use of complicated tools or other expensive equipment.

A preferred embodiment of my invention is illustrated in the attached sheet of drawings, wherein—

Figures 1 through 5 are perspective views illustrating various sequential steps in the manufacture of the improved connector of my invention;

Figure 6 is a sectional view on the general line 6—6 of Figure 3;

Figures 7 and 8 are sectional views taken on the lines 7—7 and 8—8 of Figure 4;

Figure 9 is a perspective view showing the features of a completed connector assemblage; and

Figure 10 is an enlarged fragmentary sectional view through the connector illustrated in Figure 6.

Referring to the drawing, the lead wire with which my improved connector is used preferably, comprises a flexible conductor cable 11 which is surrounded with a cylindrical sheath 13 of molded rubber or like insulating material. A woven covering 15, preferably a braid, is disposed on the outer surface of the insulating sheath 13 for the conductor cable, this covering being applied to the sheath during the manufacture of the wire.

As the first step in assembling the connector, a resilient sleeve 17 of special design, which is preferably formed of vulcanized rubber or like material, is slipped over the end of the lead wire by means of a suitable hollow tool (not shown) and is moved along the lead wire to a position such as that illustrated in Figure 2. The centrally disposed passageway 18 within the resilient sleeve 17 is cylindrical in form and throughout its length is of substantially the same diameter as the lead wire. Intermediate the ends of the sleeve 17, there is provided an annular recess 21 (see Figures 1 and 10) which connects with, and which in effect forms an enlargement of, this central passageway 18. This annular recess 21 is preferably rectangular in cross section and, as will hereinafter appear, is utilized as a positioning and locking means for the sleeve 17 in the assembled connector. The recess 21 may be conveniently formed during the molding of the sleeve.

The braided covering 15 is next removed from the outer end of the lead wire by burning or other means so as to expose a short length of the sheath 13, and a somewhat shorter section of the sheath 13 is then removed so as to bare a portion of the cable 11, as illustrated in Figure 2. Following this removal of the braid 15 from the end of the lead wire, an eyelet or ferrule 23 is slipped over the end of the exposed sheath 13, as indicated in Figures 2 and 3. This eyelet or ferrule 23 comprises a hollow, thin walled, cylindrical body portion 24 and a flanged head 25, and it is preferably formed of a ductile metal such as copper. After the eyelet or ferrule 23 has been properly located on the exposed portion of the insulating sheath 13, it is permanently fastened to the lead wire by crimping the

body portion 24, or by other suitable means. This crimping of the body portion 24 may preferably take the form of a plurality of opposed indentations as illustrated at 37 in Figures 3 and 6.

The terminal contact forming a part of the connector illustrated in the drawing comprises, as is illustrated particularly in Figures 3 and 10, a solid, generally cylindrical contact portion 28 which is formed integrally with a hollow, tubular, conductor-receiving portion 31 arranged coaxially with the contact portion 28. The inner end 33 of the central passageway within the tubular, conductor-receiving portion 31 of the terminal is of substantially the same diameter as the cable conductor 11 of the lead wire. The outer end 35 of this passageway is counterbored to receive the end portion of the lead wire to which the eyelet or ferrule 23 has been attached, see Figures 3 and 10.

The next step in the assembling of the connector consists in placing the terminal over the end of the lead wire. The relative position of the several parts at this step in the manufacture of the device is illustrated in Figures 4 and 10. The dimensions of the central passageway within the tubular, conductor-receiving portion 31 of the terminal are such that the flanged portion 25 of the eyelet or ferrule 23 will be seated snugly against the end of the terminal, the bared end of the conductor 11 will extend into the inner end 33 of the central passageway, and the portion of the sheath 13 between the ferrule 23 and the end of the lead wire will occupy the counterbore 35. With the parts in this position, the tubular terminal portion 31 is crimped adjacent the contact portion 28 so as to permanently attach the conductor cable 11 to the terminal. Particularly satisfactory results will be obtained if the crimping is performed by a device which will produce a plurality of opposed indentations as illustrated at 37 in Figures 4, 5, and 7. Also, if the crimping indentations 37 are turned with respect to each other as illustrated in the drawing, a somewhat improved electrical and mechanical connection will result.

At this point in the assembling operation, the connector is in the condition shown in Figure 4. To aid in holding the woven or braided covering 15 of the lead wire in place, the end portion of that covering is preferably unwound or otherwise removed from the sheath 13 for a short distance, and the resulting loose ends are smoothed over the outwardly projecting head portion 25 of the eyelet or ferrule 23, as illustrated in Figure 5. Next, the resilient sleeve 17 is slid from the position shown in Figure 5 to the position illustrated in Figures 9 and 10. During this movement, the annular recess 21 formed on the inside of the sleeve 17 will engage the outwardly projecting head portion 25 of the ferrule 23 and thereby serve to mechanically interconnect the sleeve and the lead wire or cord in proper position. This arrangement greatly facilitates the assembling of the device, and at the same time provides a very satisfactory fastening and positioning means for the sleeve 17 and a retaining means for the loose ends of the braid 15.

In the foregoing I have disclosed a novel form of electrical connector which is particularly suitable for use in conjunction with plug-in stationary contacts or the like. My improved con-

ector is much simpler in design than any of the comparable apparatus heretofore suggested in the art, and it is much easier to manufacture than those other structures, chiefly because of the novel fastening and positioning means utilized in connection with the sleeve 17. This fastening means for the sleeve has a further advantage in that it permits relatively easy removal of the sleeve for the purpose of inspecting the connector. Devices such as the unitary molded type connectors are not, of course, disassemblable.

Various modifications of the invention may be apparent to those skilled in the art, and it is my desire that the accompanying claims shall be construed as broadly as possible consistent with the state of the art.

I claim the following as my invention:

1. In an electrical connector, a lead wire comprising a flexible conductor having an insulating covering formed thereon, a terminal having a hollow, tubular portion for receiving one end of said lead wire, the inner end of the passageway within said hollow, tubular portion being of substantially the same cross sectional area as said conductor and the outer end of the passageway within said hollow, tubular portion being counterbored to receive said conductor with said insulating covering in place thereon, a bared end portion of said conductor extending into the inner end of the passageway within said hollow, tubular portion and being electrically and mechanically connected to said hollow, tubular portion by crimping, a ferrule which is disposed about the insulating covering of said lead wire adjacent said bared end and which is permanently attached to said lead wire, said ferrule having a tubular body portion which extends into the outer end of the passageway within the hollow, tubular portion of said terminal and having an outwardly projecting flanged portion which is disposed outside of, but closely adjacent to, the hollow, tubular portion of said terminal.

2. In an electrical connector, a lead wire comprising a flexible conductor having an insulating covering formed thereon, a terminal having a contact portion and a hollow, tubular portion for receiving one end of said lead wire therein with said insulating covering in place thereon, means electrically and mechanically connecting the conductor of said lead wire into said terminal, a ferrule having a tubular portion and a flange portion, said tubular portion of the ferrule fitting over the insulating covering of the lead wire and being attached thereto, and said tubular portion of the ferrule fitting within the hollow, tubular portion of the terminal and said flange portion of the ferrule being disposed adjacent to the outer end of said hollow, tubular portion of the terminal, and a resilient support sleeve snugly disposed about at least a part of the length of the tubular portion of said terminal and about the adjacent end of said lead wire, said sleeve being provided with an internally disposed annular recess for engaging the flange portion of said ferrule whereby said sleeve and said lead wire are mechanically interconnected, and said ferrule and said sleeve providing a strain relief connection between said lead wire and said terminal.
